CLAIM

The ornamental design for a vehicle, toy, and/or other replicas, as shown and described.

DESCRIPTION

This application is related to the following co-pending applications, filed on even date herewith: application Ser. No. 29/287,154, entitled "Rear Portion of a Vehicle, Toy, and/or Other Replicas"; and application Ser. No. 29/287,153, entitled "Taillight for a Vehicle".

FIG. 1 is a left, front perspective view of a vehicle, toy, and/or other replicas according to our novel design;

FIG. 2 is a left, rear perspective view thereof;

FIG. 3 is a left side view thereof;

FIG. 4 is a front view thereof;

FIG. 5 is a rear view thereof; and,

FIG. 6 is a top view thereof.

The broken lines are for illustrative purposes only and form no part of the claimed design. Also enclosed is a set of photographs of an embodiment of the invention.
